United States Patent

Des. 239,702
Patented Apr. 27, 1976

239,702

ABOVE GROUND SWIMMING POOL OR SIMILAR ARTICLE

Finley M. Bukaitz, Clifton, N.J., and George Neuser,
Spring Valley, N.Y., assignors to Delta Industries, Inc.,
Carlstadt, N.J.

Filed Mar. 4, 1974, Ser. No. 447,549

Term of patent 14 years

Int. Cl. D25—99

U.S. Cl. D25—2

Fig. 2.

Fig. 1.

Fig. 3.

Fig. 4.

FIG. 1 is a perspective view of an above ground swimming pool as shown in the new design.

FIG. 2 is a partial perspective view of a privacy shutter incorporated in the new design.

FIG. 3 is a side elevational view of the swimming pool according to the new design.

FIG. 4 is a top elevational view according to the new invention.

We claim:

The ornamental design for an above ground swimming pool or similar article, substantially as shown.
